UNITED STATES PATENT OFFICE.

HENRY T. WEIS, OF RIVESVILLE, WEST VIRGINIA.

AIR GUN FOR TUBE CLEANING.

Application filed November 21, 1925. Serial No. 70,657.

This invention relates to air guns and particularly to those air guns designed primarily to force cleaning plugs through tubes to be cleaned.

5 At the present time it is a custom in many plants employing tubed condensers and the like, to use plugs for cleaning tubes, by forcing the cleaning plugs into the ends of the tubes and then by placing a fluid pressure 10 pipe to the openings, apply the pressure to force the plugs through the tubes, thereby cleaning them.

This process is very slow and consequently the loss of time in forcing the plugs in the 15 ends of tubes which are slightly smaller in diameter, is considerable. It has been found to be desirable to have the cleaning plugs larger than the tube bore to insure a close fit of the plug when in the cleaning operation.

The primary object of my invention is the provision of an improved means for inserting and forcing cleaning plugs through tubes of condensers and the like.

25 Another object of my invention is the provision of a fluid operated gun for forcing cleaning plugs into and through tubes to be cleaned and having a magazine for holding the plugs and an improved means for controlling the admission of plugs from the 30 magazine.

Another and further object of my invention is the provision of a fluid operated gun for forcing cleaning plugs into and through tubes to be cleaned and having an improved 35 valve construction whereby the feeding of plugs and that of the fluid pressure are so correlated that the fluid pressure cannot be admitted until after the plug port is closed.

40 Another and still further object of my invention is the provision of such a fluid operated gun having a single valve controlling the admission of both plugs and air to the barrel of the gun.

45 Referring to the drawing wherein I have illustrated a preferred embodiment of my invention.

Fig. 1 is an elevational view of my invention.

Fig. 2 is an end view of my invention from 50 the operated end showing a portion broken away for clearness.

Fig. 3 is a longitudinal sectional view on a vertical plane.

Fig. 4 is a vertical sectional view on the 55 line 4—4 of Fig. 3.

Fig. 5 is a vertical sectional view on the line 5—5 of Fig. 3, with the plug opening closed.

Fig. 6 is a vertical sectional view on the 60 line 6—6 of Fig. 2, the inner barrel being turned to a point where the air is about to be turned on.

Fig. 7 is a perspective view of a plug.

In the following description, I shall 65 describe my invention with air pressure, although it is to be understood that any fluid pressure may be used.

In the drawing, similar reference characters are applied to the same or similar 70 parts.

Referring particularly to Figs. 1, 2 and 3, 10 designates a member which I have illustrated in the form of a tube or barrel and which is relatively rotatable about an inner barrel, designated by the reference character 75 11. This inner barrel 11 operates as a valve in a manner to be described. The outer surface of the inner barrel 11 is made a snug fit for the inner surface of the outer barrel 80 10, sufficient play only between the two surfaces being allowed to permit the inner barrel to be turned for a purpose to be described.

The outer end of the inner barrel is provided with a handle which I have illustrated in the form of the knob 12. This handle 85 12 is rigid with the inner barrel 11 and is used to turn the same within the outer barrel. A shoulder 13 registers with a recess 90 14 in the outer barrel 10 and acts as a stop to limit the movement of the inner barrel 11 in an axial direction and to the left as viewed in Fig. 3. The inner end of the inner barrel 11, is threaded for coaction with a 95 corresponding and complementary thread in a nozzle 15. This nozzle is provided with a shoulder 16 which engages the inner end of

the outer barrel 10. The delivery end 17 of the nozzle 15 is the thinnest portion and is adapted to engage the end of the condenser or other tubes to be cleaned. The 5 outer end of the inner surface 18 of the nozzle is a continuation of the inner surface 19 of the inner barrel 11.

It has been found that a better cleaning of the tubes is brought about by using plugs 10 slightly greater in diameter than the bore of the tube. In order to take care of the handling of the plugs easily, the inner surface 19 of the inner barrel 11 is made slightly larger than the plugs—enough larger to 15 permit their free entry and passage therethrough. The inner surface 18 of the nozzle 15 is tapered, the smaller end, which delivers the plugs to the tubes, being of substantially the same size as, or smaller than, 20 the bore of the tube. This tapering of the delivery end of the nozzle, causes the compression of the plug and its delivery to the tube with considerable force to aid it in the starting of the cleaning operation.

25 Situated about the outer barrel 10 of the gun and midway of its length is the magazine base member 20. This base member 20 has a cylindrical opening to receive the outer barrel of the gun and the two are preferably shrunk together. An opening or port 21 in the base member 20, coincides with an opening 22 of similar size in the outer barrel. In the inner barrel 11 is an opening 23 of similar size, shape and position which 30 registers with the opening 22 when the outer and inner barrels are in a certain position. The opening 22 in the outer barrel may, however, be closed by the body of the inner barrel, when the latter is rotated. This closing action is brought about after the admission of the plug to the inner barrel and 35 before the admission of air pressure. The openings 21, 22 and 23 are all substantially rectangular in shape to conform to the shape 40 of the plugs.

Above the opening 21 is a suitable magazine 25 for carrying the plugs to be used in the gun. This magazine as illustrated, has an opening at its upper end through which 50 the plugs are dropped. The plugs may fall on either side of the opening and collect in a line within the ring shaped body of the magazine. A stop member 26 is pivoted at 55 27 and is provided with a suitable handle 28 which may be moved from side to side and will, when moved, admit the plugs from that side, away from which the handle is moved. This is clearly illustrated in Fig. 2 in dotted lines.

60 Adjacent the magazine base member 20 is an air inlet member which I have illustrated as comprising a ring 29 having an opening of a size to fit the outer barrel 10 and having a hollow extension 30 which serves as

a handle and to conduct the air to the interior of the inner barrel as will be presently described. At the outer or lower end of the handle 30 is a threaded opening to which is attached the air hose 31. The ring 29 is preferably shrunk on the outer barrel 10 and 70 is provided with an opening 32 which connects with the air opening 33 in the outer barrel.

An opening 34 in the inner barrel is of a size similar to the opening 33 of the outer barrel 11 and is so placed as to be capable of registration with the opening 34. These openings 33 and 34 are comparatively narrow slots extending parallel to the axis of the barrels and are so arranged that they 80 cannot register with each other until after the opening 32 has closed by the relative rotation of the barrels 10 and 11. By a slight further relative rotation the openings 33 and 34 are caused to register and admit the 85 air pressure. By this construction it is clear that the air cannot be admitted until after the closing of the opening 23 which serves as the plug port.

The operation of my improved plug gun 90 is as follows:—

Assuming that the parts are in the positions shown in Fig. 3, the magazine is filled and the air pressure is turned into the pipe 95 31. The stop member 26 is moved to one side, whereupon one plug 36 will fall into the passage of the inner barrel as shown in Fig. 4. By means of the handle or knob 12, the inner barrel is turned, thus closing the 100 port 23.

The positions of the parts at the time of closing the port 23, are shown in Fig. 5. It will be noted that the ports or openings 33, 34 indicated in dotted lines, are in position to register as soon as any further movement takes place.

The gun is now held with its nozzle against the opening of the pipe to be cleaned, its position being easily maintained by pressing the body of the operator against the knob or handle 12. In this position, with the operator's hand on the extension 30, a slight rotary movement, in the opposite direction to that given the knob is given the handle 30. The openings 33, 34 will be 115 caused to register. This will connect the space behind the plug with the air pressure. The plug will immediately move toward the nozzle. Upon arrival, the nozzle will compress the plug during passage along the tapered wall 18. The plug will pass from the nozzle and through the tube, cleaning the latter.

As soon as the plug is through the tube, the extension 30 is moved in the opposite direction to move the outer barrel in the opposite direction relative to the inner barrel. This cuts off the registration of the 125

ports 33, 34 and consequently cuts off the air. The gun may then be released and while being placed against another tube opening, the inner barrel 11 may be turned 5 to admit another plug and the operation repeated.

The plug itself is made of any suitable compressible material as for example similar to the construction of the plug set forth 10 in my Patent No. 1,597,850, dated August 31, 1926.

It is to be noted that this operation can be carried on in a very expeditious manner, there being practically no time consumed 15 except that necessary to shift from one tube to another and to force the plug through the tube bore.

While I have shown and described in detail a preferred embodiment of my invention, I desire to have it understood that the showing is merely illustrative, that I do not limit myself to the exact showing and that modifications and changes may be made without departing from the spirit of my 20 invention and within the scope of the appended claims.

Having described my invention, what I claim and desire to secure by Letters Patent is:—

30 1. A gun for forcing cleaning plugs into and through pipes, comprising a barrel, an outlet extending in the same general direction as the axis of the barrel, a member pivotally mounted about the axis of the barrel, the barrel having an opening for the admission of plugs, said barrel having a chamber communicating with said opening and outlet for the respective admission and expulsion of plugs, said members 35 having a portion for closing the opening in one position of the member and means for conducting fluid pressure to the interior of the barrel.

2. A gun for forcing cleaning plugs into 45 and through pipes comprising a barrel, an outlet extending in the same general direction as the axis of the barrel, a member pivotally mounted about the axis of the barrel, the barrel having an opening for the admission of plugs, said barrel having a chamber communicating with said opening and outlet for the admission and expulsion of plugs, said member having a portion for closing the opening in one position of the member, 50 means for conducting fluid pressure to the interior of the barrel and a magazine for supplying plugs to the opening of the chamber.

3. A gun for forcing cleaning plugs into 60 and through pipes comprising a barrel, an outlet extending in the same general direction as the axis of the barrel, a member pivotally mounted about the axis of the barrel, the barrel having an opening for the admission of plugs, said barrel having a chamber

communicating with said opening and outlet for the admission and expulsion of plugs, said member having a portion for closing the opening in one position of the member, means for conducting fluid pressure to the 70 interior of the barrel, the member and barrel having ports controlling admission of the fluid pressure and so placed relative to the plug opening that when the port is open the plug opening will be closed. 75

4. A gun for forcing cleaning plugs into and through pipes, comprising a barrel having a chamber, an outlet extending coaxially with the axis of the barrel and connected to the chamber, a cylindrical shell about the 80 barrel, concentric therewith and in which the barrel is movable rotatably on its axis, the cylindrical shell enveloping the barrel, registering openings in the shell and barrel for the reception of plugs, registering ports 85 in the shell and barrel for the delivery of fluid pressure to the chamber, the openings and ports being so placed relative to each other that the openings will be out of registry when the ports are in registry and so 90 that the ports will be out of registry when the openings are in registry.

5. A gun for forcing cleaning plugs into and through pipes comprising a barrel having a chamber, an outlet extending coaxially 95 with the axis of the barrel chamber, two inlets in the barrel for admission of plugs and fluid pressure respectively, and a single means movable relative to the barrel for controlling the admission of plugs and fluid 100 pressure to the barrel chamber.

6. A gun for forcing cleaning plugs into and through pipes comprising a barrel having a chamber, an outlet extending coaxially with the axis of the barrel chamber, two 105 inlets in the barrel for admission of plugs and fluid pressure respectively and a rotatable means having an axis common to the barrel for controlling the admission of plugs and fluid pressure to the barrel chamber. 110

7. A gun for forcing cleaning plugs into and through pipes comprising a barrel, an opening at the end of the barrel for discharge of the plugs, an opening in the side of the barrel for the admission of plugs and 115 means for closing the opening at will and means for supplying fluid pressure to the barrel to propel the plug.

8. A gun for forcing cleaning plugs into and through pipes comprising a barrel, an opening at the end of the barrel for discharge of the plugs, an opening in the side of the barrel for the admission of plugs and means for closing the opening at will, means for supplying fluid pressure to the barrel to 120 propel the plug, and means for holding a plurality of plugs adjacent the opening in the side of the barrel in position to deliver one plug at a time to the barrel when the opening is uncovered. 125 130

9. A gun for forcing cleaning plugs into and through pipes comprising a barrel, an opening at the end of the barrel for discharge of the plugs, an opening in the side 5 of the barrel for the admission of plugs and means for closing the opening at will, means for supplying fluid pressure to the barrel to propel the plug, and magazine means for

holding a supply of plugs adjacent the opening in the side of the barrel, the magazine 10 having a plurality of delivery openings and switch means for controlling the delivery of plugs.

In testimony whereof I hereunto affix my signature.

HENRY T. WEIS.
